UNITED STATES PATENT OFFICE.

JOHN H. RICE, OF BOSTON, MASSACHUSETTS.

APPARATUS FOR INCREASING THE EFFICIENCY OF BOILER-FURNACES.

1,199,305.

Specification of Letters Patent. Patented Sept. 26, 1916.

Application filed September 8, 1914. Serial No. 860,774.

To all whom it may concern:

Be it known that I, JOHN H. RICE, a citizen of the United States, and resident of Boston, in the county of Suffolk and State 5 of Massachusetts, have invented certain new and useful Improvements in Apparatus for Increasing the Efficiency of Boiler-Furnaces, of which the following is a specification.

10 This invention relates to a steam generating plant which includes a boiler and a casting or setting therefor, the boiler and setting forming a more or less sinuous passage through which the products of combustion 15 pass from the furnace or fire box to a chimney or other outlet.

The chief object of the invention is to provide improved means for generating gas from oil by the heat of the products of combustion flowing through said passage, and so projecting the gas into the passage as to aid the draft and cause secondary and practically complete combustion of the unconsumed products which have escaped from 25 the fire box, so that fuel will be saved and objectionable escape of smoke prevented.

Other objects of the invention are to enable existing steam generating plants to be readily equipped with such gas generating 30 and projecting means, to provide means for conveniently inspecting the gas jet, to enable a plurality of gas jets to be projected, if desired, and to enable compressed air to be supplied with the oil for the purpose of 35 facilitating draft and secondary combustion.

The invention is embodied in the improvements which I will now proceed to describe and claim.

40 Of the accompanying drawings forming a part of this specification: Figure 1 represents a side elevation of a portion of the rear wall of a boiler setting or casing equipped with apparatus embodying my invention; 45 Fig. 2 represents a section on line 2—2 of Fig. 1; Fig. 3 represents a side view of a portion of the apparatus shown by Fig. 2; Fig. 4 represents a top view of the portion shown by Fig. 3; Fig. 5 represents an end 50 view of said portion.

The same reference characters indicate the same or similar parts in all the views.

In the drawings, 12 represents a portion 55 of a steam boiler here shown as of the fire tube type, 13 representing the fire tubes. 14 represents a portion of the casing or

setting of the boiler, this portion being a vertical wall separated from the rear head of the boiler by the usual up-take 15 through which the products of combustion pass from the furnace or fire box (not shown) through the usual horizontal passage 16 under the boiler, the said products passing over the bridge wall as usual and along the under side of the boiler to the up-take, where their 65 direction is changed, as indicated by arrows in Fig. 2.

The point indicated in the drawing where the change of direction takes place is usually known as the first turn in the passage 70 formed by the boiler and setting for the passage of the products of combustion from the fire box to the chimney or other outlet. It is to be understood, however, that my invention hereinafter described is not limited 75 to boilers and settings of the fire tube type, and may be applied to any steam generating plant including a boiler and a setting which forms with the boiler a passage more or less sinuous through which the products of combustion pass from the fire box to an outlet. 80

The wall 14 is provided with an opening 17, which is preferably provided with a lining or bushing 18 which may be installed to support brick work removed in forming the 85 opening.

In the opening 17 is placed an oil conducting and gas generating and delivering conduit preferably composed of a line of tubing and a gas delivering nozzle, said conduit being preferably adapted to bear loosely on the lower side of the opening 17 and provided at its outer end with means for detachable connection with a fixed oil supply conduit. In the embodiment of my invention here shown two separate nozzles and conduits communicating therewith are employed, but it will be understood that my invention may be embodied in an apparatus having but one conduit and nozzle. 95

The preferred form of the tubular conduit within the opening 17 is as next described.

19 represents an elongated tube portion extending practically from end to end of the opening 17, 20 represents a helically 105 coiled portion formed by bending the portion 19 as indicated, said coiled portion extending backwardly into the opening 17, and 21 represents a terminal portion preferably made in sections as indicated and 110 suitably secured to an outlet nozzle 22. The portion 20 constitutes a superheating coil

and is exposed to the heat in the up-take 15 and passage 16. The nozzle 22 is preferably a fan-shaped casting, its outer end or mouth being elongated in one direction, as indicated by Figs. 4 and 5. Oil supplied to the conduit is converted into gas while passing through the superheating coil 20, the gas, preferably mixed with compressed air as hereinafter described, being projected into the passage formed by the boiler and setting. The outlet nozzle 22 is arranged, preferably by giving its delivering end portion an inclination, as represented by Figs. 2 and 3, to project a jet 24 of gas obliquely into the said passage, and in approximately the direction taken by the products of combustion flowing through said passage. In stating that the gas jet is projected obliquely by the outlet, I mean that the path of the jet is not parallel with, but is inclined to, the path of the products of combustion, the inclination being such that the jet aids the draft and at the same time extends practically across the path of the products of combustion to prevent or reduce to the minimum the escape of unconsumed products. As shown by Fig. 2, the jet 24 is projected in an upwardly inclined direction, the outer portion of the nozzle 22 being correspondingly inclined. The upward inclination of the jet gives it a direction approximately the same as that taken by the products of combustion, as indicated by the arrows in Fig. 2, so that the draft is aided, the jet being at the same time caused to extend practically across the path of the products of combustion and act thoroughly on said products.

The nozzle 22 is preferably fan-shaped, as shown by Figs. 4 and 5, so that it projects a fan-shaped jet of wide area into the passage, the fan-shape of the jet enabling it to act effectively on the products of combustion.

When two nozzles 22 are employed they are connected by a yoke or cross-bar 25 and are arranged one above the other, the lower nozzle being preferably provided with a shoe 26 formed to rest on the lower side of the opening 17.

The outer end of the conduit portion 19 is adapted to be detachably connected with a fixed supply conduit portion 27. As here shown, the portion 19 has a bend 19° and the portion 27 a bend 27°, these bends being detachably connected by a union 28.

The opening 17 permits the jet from each nozzle 22 to be inspected from the outside. To permit such inspection, the outer end of the opening 17 is provided with a shutter preferably composed of two slidable sections 29 movable in guides formed in a flange 30 on a frame 31, which is secured to the outer side of the wall 14. The conduit portions 27 extend through orifices 32 formed in the flange 30, the unions 28 be-

ing preferably located within said flange so that the main portion of each conduit within the opening 17 may be readily removed by disconnecting the union 28. When this is done, the nozzles 22 and the conduit portions connected therewith may be readily removed from the opening 17, the shoe 26 bearing loosely on the lower side of said opening. The shutter 29 is of course closed when the apparatus is in operation and prevents the admission of air through the opening 17 in sufficient quantity to affect the draft.

33 represents an oil tank, and 34 a tank for compressed air. The oil tank may be supplied with oil through a supply pipe 35, and the air tank being supplied with air through a supply pipe 36. The tanks are connected by a pipe 37, so that a constant air pressure may be maintained on the oil in the tank 33. The portion 27 of each supply conduit is connected with the oil tank by a conduit or pipe line 38 and with the air tank by a conduit or pipe line 39, said conduits 38 and 39 being connected by a Y-piece 40 with the conduit portion 27. The conduit portions 38 and 39 are provided with globe valves 41 and needle valves 42, whereby the proportions and quantities of oil and air may be adjusted and regulated. Suitable check valves 43 are provided to prevent back pressure in the supply pipe.

A constant pressure of air is maintained in the tank 34 by any suitable means, the air supply being uncontaminated and taken from any suitable outside location.

When coal is thrown upon a fire of incandescent carbon, the heat will volatilize the hydrocarbons present, and these gases are immediately burned and by their heat bring the rest of the coal to a state of incandescence. During the burning of the hydrocarbon gases the various combinations break down and if there is sufficient oxygen present the carbon unites with it to form carbon dioxid, and the hydrogen unites with it also to form water in a gaseous state. The action is as follows:

Now if a portion of the carbon does not at once meet with sufficient oxygen it is liable to cool, and if later it comes in contact with oxygen its temperature may be too low to allow a chemical union. It then passes off as smoke. By the time all of the hydrocarbons have been burned or driven off unconsumed the remainder of the coal has become incandescent. The carbon in it will then combine with the oxygen of the air or with carbon dioxid which might be present. The union with carbon dioxid would be as follows: $C + CO_2 = 2CO$. If plenty of oxygen is present the product will

be CO_2 . If there is an insufficient amount of oxygen the product will be carbon monoxid, CO . If however the CO and free C be brought into contact with the oxygen of the air at a sufficiently high temperature they will both burn to CO_2 . This is exactly what my apparatus accomplishes, when air is mixed with the oil before combustion.

By the injection of a mixture of vaporized kerosene or fuel oil and compressed air into the smoke passage at the first turn a temperature of over 2000 degrees Fahrenheit is made possible. Pure air is used containing no deteriorating products such as consumed gases. Therefore we have the two conditions necessary to complete the combustion of the carbon monoxid and the free carbon, namely: oxygen from the air in sufficient quantity and at the necessary temperature. The evident conclusion is that secondary combustion has been made a certainty.

One pound of carbon in the coal burned to carbon monoxid yields 4400 B. T. U. and evaporates 4.55 lbs. of water from and at 212 degrees Fahrenheit. By the use of my apparatus I am enabled to complete this combustion to carbon dioxid, every pound of which yields 14,500 B. T. U. and evaporates 15 lbs. of water from and at 212 degrees Fahrenheit. By burning the free carbon to carbon dioxid I gain for every pound of carbon in the coal which has escaped as free carbon 14,500 B. T. U. A marked saving of coal is therefore effected. When it is remembered that about 80% of the heating surface of a return tubular boiler is contained in the tubes and heads, the result is obvious. Heat is added to the coldest part of the boiler. Naturally there will be a large increase in the evaporation per pound of coal or other fuel in the fire box, and since there is a secondary combustion attended with an enormous amount of ordinarily lost B. T. U. regained, the increase in evaporation will be accomplished with a great deal less coal fired.

The tubes and back head are kept clean and their heat transference efficiency increased. Being installed in the direction of the draft, there is a natural suction and increase of draft from 30% up.

My apparatus renders it unnecessary to rush the fire at times of sudden and drastic demands for steam.

There is no deteriorating effect upon the tubes, because no liquefied oil touches them. Air when compressed is heated. If the initial temperature is 60 deg. F. the compressed air will have a temperature of 175.8 deg. F. at 14.7 lbs. gage pressure, and at 70 lbs. gage pressure, our usual working pressure, it is about 410 deg. F. Therefore the oil is heated by this hot air and they are both heated by the gases coming over

from the furnace while they are passing through the superheating coils. The oil is therefore thoroughly vaporized when it passes from the burner.

The products of combustion from the furnace must pass through the gas flame because of the location of the burner.

I do not limit myself in all cases to the described provision and means for introducing compressed air with the liquid fuel, as the latter may be introduced alone, if desired.

As already stated, the apparatus may have but one gas outlet 22, instead of a plurality of outlets. These outlets may be used independently of each other, one outlet being used under ordinary conditions, and both used when a heavier load is to be provided for.

In this application and in my co-pending application filed May 12, 1913, Serial No. 767,057, I have disclosed two inventions, one, which I call the first, including a liquid fuel burner of general application and the combination of said burner with a boiler, and the other, which I call the second, including the combination of a boiler with a furnace and a liquid fuel burner to cause secondary combustion of the products from the furnace.

I have elected to claim the second invention in this application, and the first in my prior application above specified.

Having described my invention, I claim:

1. The combination with a boiler and a boiler setting, the whole forming a passage through which the products of combustion pass from a fire box to an outlet, said setting including a wall portion having an opening which communicates with said passage, of an oil conduit extending through said opening and having a delivery outlet arranged to project a jet of gas obliquely into said passage in approximately the same direction as that taken by the products of combustion, to aid the draft and cause secondary combustion, said conduit including a super-heating coil communicating at one end with said outlet and exposed to heat in said passage, and means for supplying oil to the other end of said conduit.

2. The combination with a boiler and a boiler setting, the whole forming a sinuous passage through which the products of combustion pass from a fire box to an outlet, said setting including a wall portion having an opening which communicates with a turn in said passage, of an oil conduit extending through said opening and having a delivery outlet arranged to deliver a jet of gas obliquely into the passage at said turn in approximately the same direction as that taken by the products of combustion, to facilitate the change of direction of said products, and cause secondary combustion, said conduit in-

- cluding a superheating coil communicating at one end with said outlet and exposed to heat in said passage, and means for supplying oil to the other end of said conduit.
- 5 3. The combination with a fire-tube boiler and a casing therefor forming with the boiler an uptake communicating with the receiving ends of the fire tubes, said casing having an opening which communicates with said uptake, of a conduit in said opening having a delivery outlet for gas directed in an upwardly inclined direction into said uptake toward said receiving ends to aid the draft, said conduit including a superheating coil communicating at one end with said outlet and exposed to the heated products of combustion passing through said uptake, and means for supplying oil to the other end of said conduit.
- 10 4. The combination with a boiler and its setting forming a passage through which the products of combustion pass from the fire box to an outlet, said setting including a wall portion having an opening which communicates with said passage, and a shutter adapted to close the outer end of said opening, of an oil conduit located in and supported by the bottom of said opening, and having means at its outer end for detachable connection with a fixed supply conduit, and a gas outlet at its inner end arranged to project a jet of gas obliquely into said passage in approximately the direction taken by the products of combustion, to aid the draft and cause secondary combustion, said conduit including a superheating coil exposed to heat in said passage.
- 15 5. The combination with a boiler and its setting forming a passage through which the products of combustion pass from the fire box to an outlet, said setting including a wall portion having an opening which communicates with said passage, and a shutter at the outer end of said opening, of an oil conduit located in and supported by the bottom of said opening and having means at the outer end for detachable connection with a fixed supply conduit and a fan-shaped outlet nozzle at its inner end formed and arranged to project a fan-shaped jet of gas obliquely into said passage in approximately the direction taken by the products of combustion, to aid the draft and cause secondary combustion, the fan shape causing the jet to present an extended area to the products of combustion in said passage, said conduit including a superheating coil exposed to heat in said passage and means for supplying oil to the conduit.
- 20 6. The combination with a boiler and its setting forming a passage through which the products of combustion pass from the fire box to an outlet, said setting including a wall portion having an opening which communicates with said passage, and a shutter

at the outer end of said opening, of an oil conduit located in and supported by the bottom of said opening and having a delivery outlet arranged to project a jet of gas obliquely into said passage in approximately the direction taken by the products of combustion, to aid the draft and cause secondary combustion, said conduit including a superheating coil exposed to heat in said passage, said jet being visible through said opening, and a movable shutter at the outer end of the opening.

7. The combination with a boiler and its setting forming a passage through which the products of combustion pass from the fire box to an outlet, said setting including a wall portion having an opening which communicates with said passage, of an oil conduit located in and supported by the bottom of said opening and having a delivery outlet arranged to project a jet of gas obliquely into said passage in approximately the direction taken by the products of combustion, to aid the draft and cause secondary combustion, said conduit including a superheating coil exposed to heat in said passage, said jet being visible through said opening, a frame surrounding the outer end of said opening, and a movable shutter engaged with said frame.

8. The combination with a boiler and its setting forming a passage through which the products of combustion pass from the fire box to an outlet, said setting including a wall portion having an opening which communicates with said passage, of an oil conduit located in and supported by the bottom of said opening and having a delivery outlet arranged to project a jet of gas obliquely into said passage in approximately the direction taken by the products of combustion, to aid the draft and cause secondary combustion, said conduit including a superheating coil exposed to heat in said passage, said jet being visible through said opening, a frame surrounding the outer end of said opening and having an outwardly projecting flange, which is perforated to receive said conduit, and a shutter engaged with the outer portion of the flange, the conduit being composed of sections separably connected at a point adjacent to the flange to permit the removal of the portion of the conduit within the opening.

9. The combination with a boiler and its setting forming a passage through which the products of combustion pass from the fire box to an outlet, said setting including a wall portion having an opening which communicates with said passage, of an oil conduit extending through said opening and having a delivering outlet arranged to project a jet of gas obliquely into said passage in approximately the direction taken by the products of combustion, to aid the draft and

cause secondary combustion, said conduit including a superheating coil exposed to heat in said passage, and means for supplying said conduit with a mixture of oil and compressed air.

10. The combination with a boiler and its setting forming a passage through which the products of combustion pass from the fire box to an outlet, said setting including a wall portion having an opening which communicates with said passage, of an oil conduit extending through said opening and having a delivering outlet arranged to project a jet of gas obliquely into said passage
- 15 in approximately the direction taken by the products of combustion, to aid the draft and cause secondary combustion, said conduit including a superheating coil exposed to heat in said passage, two independent reservoirs
- 20 for oil and compressed air respectively, and converging supply conduits connected with the first mentioned conduit to supply a mixture of oil and compressed air thereto, and having means for regulating the relative
- 25 proportions and quantities of oil and air supplied.
11. The combination with a boiler and a setting forming a passage through which the products of combustion pass from a fire box
- 30 to an outlet, a superheating conduit extending through a wall portion of the setting into said passage, said conduit having an

extended portion exposed to heat in said passage and an outlet arranged to project a jet of gas into said passage to aid the draft 35 and cause secondary combustion, and means for supplying said conduit with a mixture of oil and compressed air.

12. The combination with a boiler and a boiler setting, the whole forming a passage 40 through which the products of combustion pass from a fire box to an outlet, said setting including a wall portion having an opening which communicates with said passage, of an oil conduit extending through 45 said opening and having a delivery outlet arranged to project a jet of gas obliquely into said passage in approximately the same direction as that taken by the products of combustion, to aid the draft and cause secondary combustion, said conduit including a superheating coil communicating at one end with said outlet and exposed to heat in said passage, and means for supplying oil to the other end of said conduit, the conduit being 50 provided with a check valve between the source of oil supply and the said coil.

In testimony whereof I have affixed my signature, in presence of two witnesses.

JOHN H. RICE.
